UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,077,721.

Specification of Letters Patent.

Patented Nov. 4, 1913.

Application filed October 4, 1912. Serial No. 723,821.

To all whom it may concern:

Be it known that I, DAVID S. KENNEDY, a citizen of the United States, and a resident of Brooklyn, county of Kings, and State of New York, have invented a new and useful Improvement in Typographical Machines, of which the following is a specification.

My invention relates to typographical machines, having one or more magazines to contain the type or matrices, and provided with escapements to control their release and delivery therefrom. In machines of this kind, it frequently is necessary to restore displaced type or matrices to the magazine and to hold them therein, so that the latter may be shifted or replaced conveniently. For instance, in the United States Letters Patent to J. R. Rogers, No. 792,851, is disclosed a linotype machine equipped with a plurality of movable magazines, any selected one of which may be brought into operative relation to a single exterior throat provided with escapements. Before the operative magazine can be shifted, it is necessary that the matrices in the throat be restored thereto, and the said Letters Patent disclose such restoring means. When the matrices are returned to the magazine, they may be held in place by a narrow bar thrust therethrough, after which the magazine may be shifted to bring another one into operative relation to the throat, or it may be interchanged with a different magazine, without danger of the matrices being displaced.

My invention contemplates the employment of a single means for restoring the displaced matrices and for retaining them in the magazine, and specifically these means comprise a bar to engage with appropriate notches in the matrices, whereby they may be pushed upward into the magazine, the latter being provided with locking means or latches to engage the bar and thus to hold the matrices securely in place.

In the accompanying drawings, I have shown my invention in preferred form and by way of example, and as applied to a well-known type of linotype machine, but obviously many changes and variations may be made therein, and in its mode of application, without departure from its spirit.

Generally speaking, I desire it to be understood that I do not limit myself to any specific form or embodiment, except in so

far as such limitations are specified in the claims.

Referring to the drawings: Figure 1 is a transverse vertical section through a portion of a linotype machine, having my invention applied thereto; Fig. 2 is a similar view, showing certain parts in a different position; Fig. 3 is a front view, partly in section, taken substantially on the line 3—3 in Fig. 1; and Fig. 4 illustrates a matrix notched to coöperate with the restoring and holding bar.

Referring to the drawings, the magazines A are shiftably arranged with reference to the exterior throat B, so as to bring any selected one into operative relation thereto, and through this throat the matrices X pass, and then through the channel B¹ to the other assembling mechanism. The throat B is provided with a series of escapements, each consisting of a pivoted member C carrying two pawls C¹ and C², which are projected alternately into the throat B to control the release of the matrices in the well-known manner. The spring C³ tends to retract the pawl C¹ and to insert the pawl C², this tendency being resisted and controlled by the customary reed D.

All of the parts and operation so far described are or may be substantially like those disclosed in the previously mentioned Rogers patent.

As shown in Fig. 1, the throat B always contains the lower matrices X, which are held therein by the escapements, and before the operative magazine A may be shifted, it is necessary that these matrices be restored thereto. To this end, I specifically employ a bar F, which is inserted transversely through the throat B and engaged with all of the matrices in the lowermost position, and preferably in notches X¹ formed therein. This bar is then manually shifted to move the matrices longitudinally and restore them to the magazine, when the bar is locked in position by the engagement therewith of the latch or latches G carried by the magazine. It will be noted that the latch G is formed with two holding projections G¹ and G², the specific purpose of which will be hereafter explained.

To permit the restoration of the matrices to the magazine in the manner indicated, it is necessary to free them from the escapement pawls, and as these are alternately

projected into the throat B, the freeing operation must be performed in two steps. To this end, the reeds D are formed with the cuts or notches D², in which engages the projecting lip of the vertically adjustable member E, slidably mounted in the framework. The vertical adjustment of the slide E is controlled by the cam projection or projections E¹ connected to and operated by the hand lever E².

The normal position of the parts is that illustrated in Fig. 1, wherein the upper ear of the lower matrix X is sustained by the pawl C¹. After the insertion of the bar F into the notch X¹ of the matrix, the latter is moved longitudinally thereby until its lower ear abuts against the pawl C¹. The pawl is then withdrawn from the throat, by the movement of the lever E² to the dotted line position, when the matrix may be further shifted until its lower ear encounters the pawl C², as shown in Fig. 2. It is now necessary that the last-mentioned pawl be withdrawn to permit the final shifting of the matrix, and this is effected by the restoration of the hand lever to its full line position. In order to hold the matrices firmly during this operation and to prevent them from sliding back, it will be seen that at this stage the bar F is engaged by the lower holding projection G¹ of the latch G. After the withdrawal of the pawl C², the bar F may be pushed to its final position, where it is engaged by the second locking projection G² of the latch G. As previously stated, this final locking of the bar F holds the matrices in proper relation to the magazine, so that the latter may be shifted without the liability or danger of the matrices being "spilled" therefrom. Although I have shown my invention specifically as applied to a series of shiftable magazines, it will be obvious that it is similarly applicable to a single movable or interchangeable magazine, in connection with which the same necessity exists for restoring and locking the matrices. This and numerous other modifications and variations, both in the construction and application of my invention, will suggest themselves to those skilled in the art, and still be comprised within its scope.

Having thus described my invention, its construction and mode of operation, what I claim and desire to secure by Letters Patent of the United States is as follows:

1. In a typographical machine, the combination of a magazine for the type or matrices, a device disconnected from the magazine to restore displaced type or matrices thereto, and means for connecting said device to the magazine to adapt it for retaining the type or matrices therein.

2. In a typographical machine, the combination of a magazine for the type or mat-

rices, and a device adapted to be connected to the magazine to retain the type or matrices therein, the said device being adapted when disconnected from the magazine to engage and restore displaced type or matrices thereto in its movement to operative position.

3. In a typographical machine, the combination of a magazine for the type or matrices, and a locking bar detachably connected to the magazine to retain the type or matrices therein, the said bar being laterally movable into and out of the end of the magazine.

4. In a typographical machine, the combination of a magazine for the type or matrices, a movable device disconnected from the magazine to restore displaced type or matrices thereto, and locking means to engage said device at a plurality of points during its restoring movement.

5. In a typographical machine, the combination of a magazine for the type or matrices, a bar disconnected therefrom and movable bodily to restore displaced matrices thereto, and a latch formed with a plurality of locking projections to engage the bar at a plurality of points during its restoring movement.

6. In a typographical machine, the combination of a magazine for the type or matrices, an assembling throat to receive the type or matrices therefrom, a movable device to restore the type or matrices from the throat to the magazine, and means for connecting said device to the magazine after the type or matrices have been restored thereto.

7. In a typographical machine, the combination of a magazine for the type or matrices, an assembling throat to receive the type or matrices therefrom, and a bar adapted to be connected to the magazine to retain the type or matrices therein, the said bar being movable through the assembling throat to its operative position in the magazine in order to restore the type or matrices thereto.

8. In a typographical machine, the combination of a plurality of magazines for the type or matrices, an assembling throat to cooperate with any selected magazine, and a matrix retaining device for each of the magazines, the said device being movable through the assembling throat to its operative position in the magazine so as to restore the type or matrices thereto.

9. In a typographical machine, the combination of a magazine for the type or matrices, an assembling throat to receive the type or matrices therefrom, and a bar adapted to be inserted endwise in the assembling throat to engage the type or matrices and movable laterally and rearwardly therefrom into the magazine.

10. In a typographical machine, the combination of a magazine for the type or matrices, an assembling throat to receive the type or matrices therefrom, a bar adapted to be inserted in the throat to engage the type or matrices and movable rearwardly therefrom into the magazine, and devices for connecting the bar to the magazine.

In testimony whereof I hereunto set my hand this first day of October, 1912, in the presence of two attesting witnesses.

DAVID S. KENNEDY.
